(57) **CLAIM**

The ornamental design for a locking bag, as shown and described.

DESCRIPTION

FIG. 1 is a front perspective view of a locking bag of the present application;

FIG. 2 is a front elevational view of the bag of FIG. 1;

FIG. 3 is a top plan view of the bag of FIG. 1;

FIG. 4 is a back elevational view of the bag of FIG. 1;

FIG. 5 is a bottom plan view of the bag of FIG. 1;

FIG. 6 is a left side elevational view of the bag of FIG. 1; and,

FIG. 7 is a right side elevational view of the bag of FIG. 1. The dashed lines illustrate portions of the locking bag and form no part of the claimed design.
